UNITED STATES PATENT OFFICE

HENRY WESLAKE, OF LONDON, ENGLAND

CARBURETOR FOR INTERNAL-COMBUSTION ENGINES

Application filed September 19, 1925, Serial No. 57,406, and in Great Britain August 4, 1925.

This invention relates to carburetors for internal combustion engines, and especially to carburetors in which the mixing or choke tube is horizontally disposed.

5 The invention has among its objects to render the operation of the engine most efficient at determined speeds.

The invention comprises the features hereinafter described.

10 The invention is hereinafter described by way of example with reference to the accompanying diagrammatic drawing in which

Figure 1 is a sectional elevation of a carburetor provided according to the invention,

15 Figure 2 is a part sectional plan view corresponding to Figure 1,

Figures 3 and 4 are detail views of the nozzle in plan and sectional elevation respectively, and

20 Figures 5 and 6 are detail views in sectional elevation and plan respectively of a modified construction of nozzle.

In carrying the invention into effect according to one construction and with reference to Figures 1 to 4 of the accompanying drawing I provide the mixing or choke tube *a* horizontally disposed with one end advantageously outwardly flaring, while the other is adapted for connection by suitable means

25 to the induction pipe.

The float chamber *b* is disposed in such position in relation to the flat nozzle *c* that the normal level of liquid in the float chamber is immediately below the central plane 30 of the nozzle. The float chamber *b* is adapted for connection beneath the mixing or choke tube *a*, and for this purpose the tube *a* may be provided with a downwardly extending boss fitting *a*¹, having at its upper end a recess adapted for the reception of the enlarged

35 lower end *c*² of the tubular stem *c*⁶, by which the nozzle *c* is supported in a horizontal position within the mixing tube, and through which the volatile liquid may pass through

40 to the central cavity *c*¹ in the nozzle *c*. The float chamber *b* is provided at its lower end with an outwardly extending arm *b*¹ in which a channel *b*² is provided for the outward passage of the volatile liquid, and at the end of

45 50 the arm, a tubular boss *b*³ is provided adapt-

ed for insertion within the downwardly extending boss fitting *a*¹, and the tubular boss *b*³ may be adapted for the reception of a plug *d* having an axial bore hole, which plug is screw threaded externally for engagement 55 with an internal screw thread at the enlarged lower end *c*² of the tubular stem *c*⁶ by which the nozzle *c* is supported; and at the lower end the plug *d* may be provided with an external annular groove *d*¹, and a transverse 60 hole *d*², whereby the volatile liquid flowing from the channel *b*² into the annular space surrounding the plug at the position at which the groove *d*¹ is provided, may pass through the transverse hole *d*² into and through the 65 axial bore hole in the plug *d* and thence through to the nozzle *c*.

The mixing or choke tube *a* may be provided with a transversely disposed throttle valve *e* adjacent the front of the nozzle *c*, 70 which valve may be adapted to slide so as partially or wholly to close the mixing or choke tube *a*, and so as also partially or wholly to close the nozzle orifice *c*³. For this purpose the front of the nozzle *c* is straight, 75 and lies adjacent to the valve *e*. The valve *e* may be provided as a hollow cylinder closed at its outer end, and may be mounted within a transversely disposed part *a*² of the mixing or choke tube *a* of a corresponding form, 80 and it may be subject to the action of a helical spring *e*¹ tending normally to close it, and it may be operable by means of a Bowden transmission wire *e*², the operating lever of which may be adapted to be set into determined positions. Thus on being so set the cross sectional area of the mixing tube *a* may be varied by the valve as well as the outlet orifice *c*³ of the nozzle *c*. 85

The nozzle *c* may be provided advantageously of two parts, that is to say, a lower or base part *c*⁴ and a top part or cover plate *c*⁵. The lower or base part *c*⁴ may be provided with a recessed or dished central part, the sides of which are inclined inwardly towards the rear, whereby on the top part or cover plate *c*⁵ being applied in position the cavity *c*¹ is formed which is gradually reduced in width towards the rear, where the inlet for volatile liquid is provided through 90 95 100

the tubular stem c^6 , by which the nozzle c is supported as hereinbefore described. At the front a narrow outlet orifice c^3 is provided which for example may be of about 8/1000ths 5 of an inch wide and about 1/8 of an inch in depth, while the width of the cavity c^1 formed within the nozzle c as described, may be for example about 40/1000ths of an inch.

A series of holes c^7 or a slot or slots may be 10 provided over the narrow or contracted part of the nozzle c , and the series of holes c^7 , or the slot or slots may be interrupted, as and for the purpose hereinbefore described, or certain of the holes may be closed by plugs of 15 suitable form.

In Figure 3 the positions of the series of holes are shown interrupted at the left, so that thus a richer mixture may be provided on the valve being fully opened. It will however be understood that the interruption may 20 occur at the middle of the nozzle or at the opposite side, and that the sizes of the holes may be varied in particular positions.

According to a modified construction of 25 the nozzle as illustrated in Figures 5 and 6, the nozzle is provided in two separate parts c^8 , c^9 , disposed in adjacent positions, each part being formed of a lower or base part c^4 and a top part or cover plate c^5 , and being 30 provided with a stem c^6 , central cavity c^1 and orifice c^3 as hereinbefore described. In this construction however the series of holes c^7 or a slot or slots are provided only in one part c^8 of the nozzle; or the series of holes or the 35 slot or slots may be provided in each nozzle and may be interrupted for the purposes hereinbefore described.

The mixing or choke tube a may be provided at the rear of a rectangular transverse 40 cross section, comprising parallel vertically disposed walls a^3 , and parallel horizontally disposed walls a^4 which latter flare outwardly at the rear. The upper horizontal wall a^4 at its outwardly or upwardly flaring rear 45 end has hinged to it at the outer edge a movable wall a^5 of an outwardly flaring shape, similar to that of the oppositely disposed wall, but so disposed that its inner end a^6 extends to a position adjacent the throttle valve 50 e or the front of the nozzle c . The movable wall a^5 thus provided extends completely across from one vertical wall a^3 to the other and in one position it may lie adjacent the upper wall a^4 of the mixing tube a , while in 55 the other its inner end a^6 may lie in position adjacent the top face of the nozzle c . By such means the mixing or choke tube a in position above the nozzle c may be adjusted in cross sectional area to the extent desired. 60 The movable wall a^5 may thus by means of a Bowden transmission wire a^7 , the central part of which is connected to its inner end, be caused to assume any desired position between the extreme positions indicated.

65 The apparatus described is of general ap-

plication, but is especially applicable to motor-cycles. It will be understood that any type of throttle valve other than indicated may be used, but that the edge of the nozzle may be formed to correspond to the face of the valve; thus for example the face of the valve and the edge of the nozzle may be straight or convex or concave. Double or multiple nozzles such as described with reference to Figures 5 and 6 are more especially 70 intended to use with carburetors for motor vehicles and any one or more of the nozzles may have the series of holes or slots interrupted, or the holes or slots of varying diameter or width. The nozzle or nozzles may be reduced at the front where the top and bottom faces may be inclined inwards towards the outlet orifice, and this is in general preferred where the utmost efficiency is desired. 75

I claim:—

1. A carburetor comprising in combination 80 a mixing tube substantially horizontally disposed, a transversely disposed throttle valve provided in the said mixing tube, a nozzle disposed within the said mixing tube said nozzle being substantially horizontally disposed with its outlet end adjacent the periphery of the said throttle valve, in a plane parallel with the axis of the said throttle valve, said nozzle being adapted for the passage 85 through it of the volatile liquid fuel, and having at its upper part adjacent its outlet end only air admission apertures which extend to within the interior of the said nozzle adjacent the outlet end, substantially as described. 90

2. A carburetor comprising in combination 95 a mixing tube substantially horizontally disposed, a transversely disposed throttle valve provided in the said mixing tube, a nozzle disposed within the said mixing tube said nozzle being substantially horizontally disposed with its outlet end adjacent the periphery of the said throttle valve, in a plane parallel with the axis of the said throttle valve, said nozzle being adapted for the passage 100 through it of the volatile liquid fuel, and having at its upper part adjacent its outlet end only air admission apertures which extend to within the interior of the nozzle adjacent the outlet end, said apertures not 105 extending completely across the top of the nozzle, substantially as described. 110

3. A carburetor comprising in combination 115 a mixing tube substantially horizontally disposed, a transversely disposed throttle valve provided in the said mixing tube, a nozzle disposed within the said mixing tube said nozzle being substantially horizontally disposed with its outlet end adjacent the periphery of the said throttle valve, in a plane parallel with the axis of the said throttle valve, said nozzle being adapted for the passage through 120 it of the volatile liquid fuel, and having at its upper part adjacent its outlet end only air 125

admission apertures which extend to within the interior of the nozzle adjacent the outlet end, said apertures being of variable dimensions, substantially as described.

4. A carburetor comprising in combination
- 5 a mixing tube substantially horizontally disposed, a transversely disposed throttle valve provided in the said mixing tube, a plurality of independent flat nozzles disposed within
  - 10 the said mixing tube, said flat nozzles being substantially horizontally disposed with their respective outlet ends adjacent the periphery of the said throttle valve, in a plane parallel with the axis of the said throttle valve, said flat nozzles being adapted for the passage
  - 15 through them of the volatile liquid fuel, one or more of said flat nozzles having air admission apertures formed on their upper parts which apertures extend to within the
  - 20 interior of the respective nozzle adjacent the outlet end only, substantially as described.

5. A carburetor comprising in combination
- a mixing tube substantially horizontally disposed, a transversely disposed throttle valve
  - 25 provided in the said mixing tube, a flat nozzle disposed within the said mixing tube, said nozzle being substantially horizontally disposed with its outlet end adjacent the periphery of the said throttle valve, in a plane parallel with
  - 30 the axis of the said throttle valve, a valve within the mixing tube and disposed in position above the said nozzle, the said valve being hinged near the inlet end of the mixing tube away from the throttle valve and being
  - 35 adapted to be lowered on its hinge to vary the cross-sectional area of the tube above the nozzle and between the said nozzle and the upper part of the said mixing tube only, and mechanical means for the manual operation of the said hinged valve, substantially
  - 40 as described.

HENRY WESLAKE.
